UNITED STATES PATENT OFFICE.

FERDINAND SCHMIDT, OF DES MOINES, IOWA.

DESIGN FOR A GOBLET OR SIMILAR ARTICLE.

Application filed March 14, 1927. Serial No. 21,125. Term of patent 7 years.

To all whom it may concern:

Be it known that I, FERDINAND SCHMIDT, a citizen of the United States, and a resident of Des Moines, in the County of Polk and State of Iowa, have invented a certain new, original, and ornamental Design for a Goblet or Similar Article, of which the following is a specification, reference being had to the accompanying drawing, forming part thereof.

I claim:

The ornamental design for a goblet or similar article, as shown.

FERDINAND SCHMIDT.
